UNITED STATES PATENT OFFICE.

WILLIAM T. GIBERSON AND DAVID R. ANDERSON, OF TOMS RIVER, NEW JERSEY.

RECLINING-CHAIR.

1,160,399.

Specification of Letters Patent. Patented Nov. 16, 1915.

Application filed April 23, 1912. Serial No. 692,675.

To all whom it may concern:

Be it known that we, WILLIAM T. GIBERSON and DAVID R. ANDERSON, citizens of the United States, residing at Toms River, in the county of Ocean and State of New Jersey, have invented certain new and useful Improvements in Reclining-Chairs, of which the following is a specification.

This invention relates to that class of reclining chairs in which the seat frame, back-frame and leg rest are, or may be, operable simultaneously to shift said parts to different positions of adjustment; a good illustration of this type of chair being found in Patent No. 535,999, dated March 19, 1895.

The object of this invention is to improve the type of chairs referred to in particulars of construction and operation.

With this object in view, our invention consists in duplicate rectangular hinge-frames to be supported by a chair base and adapted to carry the seat-frame, back-frame, leg-frame and the horizontal and upright sections of the arms.

It further consists in mechanism operable by a person while occupying a chair to adjust the seat, back and leg-frames, and the arms by the slight movement of a normally locked lever, and to lock the parts against accidental movement.

It further consists in details of construction and in combinations, which will be hereinafter described and claimed.

In the accompanying drawings, illustrating one embodiment of our invention: Figure 1 is a side elevation of a chair, broken lines being used to indicate a different position of adjustment of the back-frame and leg-frame. Fig. 2 is a vertical section 40 of the same, taken through the seat, back and leg-frames. Fig. 3 is a similar section showing the parts in a different position of adjustment, also showing, in section, a detail of the arm construction. Fig. 4 (Sheet 45 1) is a detail elevation showing the housing to protect the outer operating gearing. Fig. 5 illustrates a modification. Fig. 6 illustrates, in elevation, and partial section, the outer operating gearing. Fig. 7 is an enlarged sectional detail of a journal stud of the hinge frame and its bearing. Fig. 8 is an enlarged detail of a part of the rod connecting the lower extension of the back-frame and the leg-frame.

50 The same reference characters are used in the several figures to indicate identical parts.

We employ any suitable base, that here shown comprising two stout side frames A and A' rigidly connected together by horizontal braces a . These side frames are provided at front and rear with upward extensions a' and a^2 having bearings A^2 therein, in which are journaled stub-shafts or studs 1 and 2 projecting from the shorter members 3 and 4 of two hinge-frames comprising said shorter members 3 and 4, to the ends of which are jointed the ends of the long upper and lower horizontal members 5 and 6 of said frames.

The seat-frame 7 is securely bolted to the lower horizontal member 6 of the hinge-frame, and is carried thereby, and the back-frame 8 is in like manner bolted to the rear shorter member 4 of the hinge-frame, and carried thereby, the upper margin of the leg-frame 9 being hinged to the forward edge of the seat-frame, as shown in Figs. 2 and 3, and the side bars of the back-frame being extended below the seat-frame.

The forward shorter member 3 of the hinge-frame carries a finishing piece 10, and to the upper horizontal members 5 of said hinge-frame are secured the arm pieces 11, which are provided at their forward ends with recesses 12 to receive the upper ends of 85 the ornamental finishing pieces 10, as shown in Fig. 3.

To the under side of the seat-frame 7 is secured a rack-bar 13, which is engaged by a toothed cam-shaped segment 14 mounted 90 on a horizontal shaft 15 which is journaled at its ends in bearings secured to the well forward of the side-frames A A' of the base. The shaft 15 projects at one end beyond its bearing, here shown as the right hand end, and rigidly secured to said projecting end is a half-pinion 16 engaged by a toothed sector 17 carried by or formed integral with the end of a lever 18 pivoted at 95 19 to the bracket 20 which, as shown in Figs. 1 and 6, carries the bearing for the shaft 15. Projecting outwardly from the upper inner corner of the bracket 20 (see Fig. 6) is an internally toothed flange 21, curved to an arc having its center in the pivot 19 100 (which extends through the leg of frame A), the teeth of said flange being engaged by a dog 22 secured to or forming part of a push-rod 23 which is movable longitudinally in guides of the lever 18, and held 110 normally in its uppermost position, with the dog 22 engaging between adjacent teeth

of the flange 21, by a compression spring 24 bearing at its lower end on a shoulder of the lever 18, the upper end bearing against a cross-pin 25 carried by the push-rod 23.

5 From the foregoing description it will be evident that upon pressing upon the top of the push-rod 23 its dog 22 will be freed from the teeth of the flange 21, and that then upon movement of the lever 18 in the direction of the arrow, Fig. 1, the seat-frame, back-frame and arms may be caused to assume the position shown in Fig. 3, or any intermediate position, and the parts locked by removing pressure from the push-rod.

10 15 The side pieces of the back-frame 8 are extended downward (see broken lines, Fig. 1) and to the lower end is pivoted one end of a connecting rod 26, the outer end of which is adapted for connection with any 20 one of several apertures in a bracket 27 secured near the lower end of the leg-frame. By this construction the occupant of a chair may adjust the seat-frame and back-frame to different positions without leaving his 25 seat, and also adjust the leg-frame by the same movement of the lever, provided the connecting-rod 26 is in engagement with the bracket 27, and not folded back upon itself and secured to the lower extension of the 30 back-frame. The joint 26^a of said connecting-rod is similar in operation to the well known joints in top-props for carriages, locking past centers when extended to insure the extended position of the parts until 35 force is exerted to fold them one upon the other.

While it is apparent that the chair so far described may be constructed of wood or metal, it is our purpose to employ wood in 40 the manufacture, and, therefore, it will be expedient to provide metal bearings for the metal journal-pins 1 and 2 of the metal hinge-frame. Such bearings are illustrated in Fig. 7, and comprise sleeves 28 flanged 45 at one end to be inserted in appropriate apertures in the extensions *a'* of the base-frame. The journal studs 1 of the hinge-frame have bearing in these sleeves or bushings, said studs being somewhat shorter 50 than the thickness of the base-frame extensions *a'* and having projecting threaded ends upon which are seated dished washers 29 bearing upon the surface of said extensions, nuts 30 being threaded upon the threaded 55 ends of the studs. This arrangement prevents the journal studs 1 of the hinge-frame from working out of their bearings and tends to strengthen the upper part of the base-frame. To give exterior finish, these 60 parts will be covered at the outer ends by an ornamental stamping 31.

A modified form of operating devices is shown in Fig. 5, wherein, instead of the straight rack-bar and cam-shaped segment, we employ a pinion 44 on the shaft 15 to engage a concaved rack 43 on the seat-frame. This enables us to locate the shaft 15 closer to the seat-frame, which may be preferable to some purchasers. The operation of the parts will necessarily be the same.

70

It will, of course, be understood that the drawings are merely illustrative of a practically operating chair, and that in the practical manufacture the frames will be caned or upholstered, and the various parts made 75 symmetrical and attractive to the eye.

Claims:

1. In a chair of the character described, the combination of a base frame having upward extensions and bearings therein; a 80 pair of hinge-frames having studs journaled in said bearings; a seat-frame, back-frame, and arms rigidly secured to members of said hinge-frames; a leg-frame hinged at top to the front rail of the seat-frame, and 85 detachably connected at its lower end to the lower end of the back-frame; a rack secured to the seat-frame; means carried by the base frame to move the seat frame, back frame, arms and leg frame, embracing a shaft, 90 gears on said shaft, one meshing with the rack of the seat-frame and the other located exteriorly of the base frame; and a hand lever fulcrumed on the base frame and having a geared sector engaging the exterior 95 gear of the shaft.

2. In a chair of the character described, the combination of a base frame having upward extensions and bearings therein; a pair 100 of hinge-frames having studs journaled in said bearings; a seat-frame, back-frame and arms fixed to members of the hinge-frames; a rack secured to the seat-frame; bearings secured to the base frame; a shaft journaled in said bearings, having a gear engaging the rack of the seat-frame, and extended at one end; a bracket secured to the base frame and provided with a bearing for the extended end of the shaft; a pinion mounted on said shaft outside said bracket; a lever fulcrumed on said bracket having a toothed sector engaging said pinion; a toothed sector formed on said bracket; and a dog carried by the lever to engage said last named sector.

110

In testimony whereof we affix our signatures in presence of two witnesses.

WILLIAM T. GIBERSON.
